[57] CLAIM

The ornamental design for a display stand or similar article, as shown and described.

DESCRIPTION

FIG. 1 is a front elevational view of a display stand or similar article showing our new design;

FIG. 2 is a right side elevational view thereof;

FIG. 3 is a top plan view thereof;

FIG. 4 is a rear elevational view thereof;

FIG. 5 is a bottom plan view thereof;

FIG. 6 is an enlarged cross-sectional view taken along line 6—6 of FIG. 1; and

FIG. 7 is an enlarged fragmentary view taken along line 7—7 of FIG. 6.

FIG.1
